ALBERT H. HOOKER, OF NIAGARA FALLS, NEW YORK, ASSIGNOR TO HOOKER ELECTRO-CHEMICAL COMPANY, OF NEW YORK, N. Y., A CORPORATION OF NEW YORK.

ELECTROLYTIC CELL.

1,075,570.

Specification of Letters Patent. Patented Oct. 14, 1913.

Application filed February 26, 1912. Serial No. 679,897.

To all whom it may concern:

Be it known that I, ALBERT H. HOOKER, a citizen of the United States, residing at Niagara Falls, in the county of Niagara and State of New York, have invented certain new and useful Improvements in Electrolytic Cells, of which the following is a specification.

This invention relates to cells of the diaphragm type for the electrolysis of alkali-metal chlorid solutions between approximately vertical insoluble anodes and permeable or perforated cathodes with which the diaphragm is in contact, and to methods involved in the operation of such cells, a primary object of the invention being to provide a form of cell possessing great ampere-capacity in conjunction with relatively low starting and operating voltages.

20 I have discovered that in cells of the particular type above described there exists a heretofore unnoted relation between the voltage of the cell in operation, and the vertical height of the diaphragm, the other conditions affecting the voltage, as for example, the current density at the electrode surfaces, the distance between the electrodes, the material of the anodes, the resistance of the diaphragm, and the concentration of the electrolyte, being the same. Based on this discovery, I am enabled to construct cells of large ampere capacity, as for example cells capable of transmitting 2000 to 6000 amperes or more, but capable nevertheless of operating at the comparatively low voltages which are feasible with electrolytic cells of relatively small dimensions and capacity.

40 I have found in the practical operation of electrolytic cells of the above defined type, and particularly when such cells are operated at current densities approximating or exceeding 100 amperes per square foot of electrode surface, that if it be attempted to increase the ampere-capacity of the cell by increasing proportionately the vertical and horizontal dimensions of the electrodes, the larger cell will require a distinctly higher operating voltage, the conditions as to current density, etc., remaining the same. According to the present invention, I am enabled to construct cells of this type, which possess the desired larger ampere-capacity, and are nevertheless capable of operating at high current densities and at voltages not in excess of the economical maximum.

For a full understanding of the invention, reference is made to the accompanying drawings wherein—

Figure 1 graphically illustrates in the form of curves certain observed relations 60 between the vertical height of the diaphragm and the starting and operating voltage of the cells, under conditions otherwise approximately comparable, except with respect to the temperature of the electrolyte. 65 Fig. 2 is a side elevation, partly broken away, of one form of electrolytic cell embodying the invention.

In Fig. 1, the curves marked A, B, C and D indicate respectively the voltage-characteristic of electrolytic cells of the type herein defined, at the range of current densities indicated, the current density being computed on the basis of the cathode area. The cathodes consisted in each case of perforated 70 metal sheets covered by the diaphragm on the side adjacent the anode, but the effective area of the cathode is computed as that of an imperforate sheet of equal dimensions. The descriptive character of the several cells 75 reduced to a common area was as follows:

A:—Cathode 32 inches long by 36 inches high; area 1152 square inches; ratio of height to length=1:0.889.

B:—Cathode 48 inches long by 24 inches 85 high; area 1152 square inches; ratio of height to length=1:2.

C:—Cathode 64 inches long by 18 inches high; area 1152 square inches; ratio of height to length=1:3.555.

D:—Cathode 96 inches long by 12 inches high; area 1152 square inches; ratio of height to length=1:8.

It will be noted that the cathode area is the same in all cases, and it might have been 95 assumed that at equal current densities the starting and operating voltages would likewise be identical. Actual trial however has shown that this is far from being the case. For example, if a current of 1000 amperes, corresponding to 125 amperes per square foot of cathode area, be passed through each cell, the starting voltages are found to be as follows: A starts at 4.96 volts, B starts at 4.40 volts, C starts at 4.07 volts, D starts at 3.70 100 volts. At higher or lower current densities a similar relation exists, as clearly indicated by the drawing, the differences in the starting voltages becoming greater as the current densities increase. A current of 1000 am- 110

peres flowing to cathodes of dimensions as above specified, would of course correspond to 2000 amperes for each cell of the standard double-cathode type, as described for instance in United States Patent No. 779,383, or as herewith illustrated.

Referring to Fig. 2, 1 represents the concrete cell-body, resting upon insulating supports 2. 3 are anodes of graphite, carried by concrete blocks 4, and connected to the anode bus bars 5. 6 are the recessed metal side plates, detachably secured by clamps 7 which bear upon the fixed angle-iron framework 8. 9, 9 represent the cathode connections to the side plates 6. 10 is one of the vertical cathode plates of perforated steel, secured at its margin to the inner face of the recessed side plates 6, and covering the recessed portion thereof. 11 is the diaphragm of asbestos paper or the like overlying the cathode on the side adjacent the anode. 12 is the brine inlet, and 13 the overflow for chlorinated brine, the level of which may be controlled by longitudinal adjustment of the glass tube 14, which is of sufficient capacity to afford passage also for the gaseous chlorine. Caustic liquor is withdrawn through pipes 15, flowing through funnel 16 to the caustic main 17. 18 is an overflow for hydrocarbon liquid, when this is used, and 19 a cock for draining the cathode compartment, both overflow and cock discharging into a funnel 20 leading to the main 21.

It will of course be understood that the starting and other voltages shown on Fig. 1 are not absolute, inasmuch as the voltage depends upon many factors, including the distance between the electrodes, the material of the electrodes, the temperature and concentration of the electrolyte, etc.; but other conditions being alike, the starting voltage varies directly with the height of the diaphragm, in approximately the manner indicated. During the operation of the cell, the voltage, as a rule, exhibits a tendency to rise slowly, as the porosity of the diaphragm is reduced. The several curves indicated illustrate the effect of a variation in height in conjunction with a corresponding temperature variation, inasmuch as a cell operating at a relatively low voltage will of course tend, except as the temperature may be independently controlled, to a relatively low temperature. The effect of operating these several cells under identical temperature conditions would be to increase somewhat the divergence of the several curves, and further to accentuate the advantage of the type of construction embodying the higher ratio of the horizontal dimension of the cathode to its vertical dimension. Based upon this heretofore unobserved relation between the vertical height of the cathode and the cell voltage, I have been able to design cells of very large ampere-capacity, which

are capable of operating at high current densities and at economical voltages. For example, assume that it is desired to construct a cell of standard type having a capacity of 2000 amperes, to operate at a starting voltage of 3.5 at 100 amperes per square foot of cathode area. The chart shows at once that this starting voltage at this current density is characteristic of a cathode approximately 12 inches in height, under standard conditions as regards the character of the diaphragm, distance between electrodes, etc. It follows that the total length of the cathode must be approximately 20 feet, corresponding in a cell of the usual double-cathode type, to two cathodes, each 12 inches high by 10 feet long. For cells of larger ampere capacity it is often economical to increase somewhat the height of the cathode, in order to avoid engineering difficulties arising from an excessive length of the cell body. For example, a 4000 ampere cell may be constructed with a cathode 18 inches high, each cathode being 13½ feet in length; the starting voltage of such a cell at a current density of 100 amperes per square foot will be about 3.85 volts. If, however, conditions permit the construction of a longer cell, the diaphragm and cathode may be reduced in height, such reduction affording a reduction in the starting voltage of the order of magnitude shown by the chart or diagram.

It follows directly from the foregoing considerations that it is highly advantageous, from the point of view of energy efficiency, to construct the cell with long and relatively low cathodes, having of course due regard to the necessary strength of the cell-bodies, which are usually constructed of reinforced concrete, and to the additional floor space requisite for the long cells. The most economical type of cell will depend, therefore, upon a variety of factors; but by the aid of the foregoing considerations it is easy, by taking account of such factors, to design a cell having the desired characteristics. It is to be noted that considerations of high energy efficiency require in all cases that the cathode should be relatively long and low; and in the case of cells having a capacity of 2000 amperes or over, that the length of a single cathode, in case of the standard double-cathode cells, should be at least six and one-half times its vertical height, and preferably more than this. In case the cell has two cathodes, as in the standard double-cathode cell, the aggregated or total longitudinal dimension of the two cathodes should be at least thirteen times the vertical height of a single cathode, and preferably more than this. This involves a radical departure from cells as heretofore designed, in which it has been usual to increase the cathode area by a proportionate or approxi-

mately proportionate increase of its horizontal and vertical dimensions.

It is to be understood that the principles above stated are applicable to cells having a single diaphragm and cathode, and also to cells of the standard type having opposite cathodes with associated diaphragms, it being essential only in the latter case that the combined horizontal dimension of the diaphragms, should be at least thirteen times the vertical dimension of a single diaphragm. It is immaterial to the application of these principles whether or not the cathodes present plane surfaces. In case of cylindrical or similar cells, the circumferential length of the cathode is to be regarded as its horizontal dimension.

The above described relation between the vertical height of the cathode and the cell-voltage has been observed by me only in cells liberating a gaseous anode product, as chlorin, and it may be assumed, as explaining at least in part the observed relation, that the increased voltage is due to the presence in the vertical column of electrolyte between the electrodes, of gas bubbles, the proportion of which tends to increase with the height of the column, and with the current density. This explains also why the relation noted becomes more strongly accentuated as the current density is increased, and why the low vertical height of cathode is essential to the economical opera-

tion of cells having a capacity of 2000 amperes or more. The expression "high 35 amperage cell" as used in the claims is accordingly intended to define a cell having a capacity of at least 2000 amperes under normal working conditions.

I claim:—

1. A high-amperage cell for the electrolysis of alkali-chlorid solutions, comprising an insoluble anode, a permeable cathode and an interposed diaphragm in contact with said cathode, said electrodes being approximately vertically disposed, the horizontal dimension of the cathode being in excess of six and one-half times its vertical-dimension, as and for the purposes set forth.

2. A high-amperage cell for the electrolysis of alkali-chlorid solutions, comprising an insoluble anode, and a plurality of permeable cathodes with interposed diaphragms in contact therewith, said electrodes being approximately vertically disposed, the aggregated horizontal dimensions of the cathodes being in excess of thirteen times the vertical dimension of one of said cathodes.

In testimony whereof I affix my signature 60 in presence of two witnesses.

ALBERT H. HOOKER.
